United States Patent Office.

LUCIUS PARMALEE WILDMAN, OF DANBURY, CONNECTICUT.

Design No. 4,866, dated May 2, 1871.

DESIGN FOR A BOW INSTRUMENT.

The Schedule referred to in these Letters Patent and making part of the same.

To all whom it may concern:

Be it known that I, LUCIUS PARMALEE WILDMAN, of Danbury, in the county of Fairfield and State of Connecticut, have invented a new and Original Design for a Bow Instrument; and I do hereby declare that the following is a full, clear, and exact description thereof, which will enable others skilled in the art to make and use the same, reference being had to the accompanying drawings forming part of this specification.

The drawings represent a face view of my new design for bow instrument.

The invention relates to a new configuration of apertures through the sounding-boards of violins, violas, violoncellos, and double basses; and consists in making said apertures crescent-shaped, and arranging them near the edges of the sounding-board.

A in the drawings represents the sounding-board of the instrument.

a a are the apertures cut through the same.

They are crescent-shaped, as shown, and placed as far apart as practicable, so that the uninterrupted portion *b* of board between them will be of considerable width.

Aside from the novel appearance thus obtained, the practical advantage is gained over other instruments of the same class that more uninterrupted length of fiber will be left in the sounding-board and the latter left stronger than with the ordinary *f*-shaped apertures. The sound capacity of the instrument and its actual and artistic value are consequently augmented by my invention.

I claim as my invention—

The design for the sounding-board of a bow instrument, as shown.

L. P. WILDMAN.
